UNITED STATES PATENT OFFICE

CHESTER I. HALL, OF FORT WAYNE, INDIANA, ASSIGNOR TO GENERAL ELECTRIC COMPANY, A CORPORATION OF NEW YORK

ELECTRICALLY-WOUND CLOCK

Application filed November 18, 1927. Serial No. 234,265.

My invention relates to a constant torque motive mechanism which is suitable for general application but which is particularly adapted for use in spring driven clock movements where a small electric motor is employed for winding the spring.

The time keeping qualities of the ordinary hand wound spring driven clock movement are impaired by reason of the fact that the 10 clock escapement is required to regulate the speed between wide limits of the main spring tension. In the eight day clock for example, when the spring is fully wound, the escapement mechanism is subjected to considerably 15 more tension than exists when the spring is nearly unwound. As a result the beat of the escapement tends to vary somewhat with the tension of the main spring. This varying condition may be compensated for to some 20 extent but at the expense of added complications and cost. To avoid the conditions above mentioned it has been proposed to maintain the clock spring wound to a substantially 25 constant tension by automatic means, such as an electric motor, together with means dependent upon the condition of the spring for controlling the motor.

My invention relates to improvements in devices of the last mentioned group and its 30 principal object is to provide a simple, inexpensive but reliable mechanism for maintaining the clock spring wound to a very uniform tension. In carrying my invention into effect I provide means responsive to the counter 35 torque of the main spring for controlling the winding torque transmitted thereto from the winding motor. In the preferred form of my invention a worm gear is provided between the winding motor and the spring 40 through which the winding torque is transmitted. There is produced an endwise thrust 45 on the worm proportional to the transmitted torque and the worm is permitted to move endwise in response to this thrust to control the speed of the driving motor, preferably through a friction brake.

The features of my invention which are believed to be novel and patentable will be pointed out in the claims appended hereto. 50 For a better understanding of my invention

reference is made in the following description to the accompanying drawing in which Fig. 1 represents an expanded perspective view of my invention as applied to a clock; Fig. 2 shows the details of the preferred form 55 of the torque controlling mechanism as applied directly to an electric motor of the induction disc type in which the endwise end thrust of the worm shaft is opposed by resilient yielding means such as a spring; Fig. 2^a 60 represents an end view of one of the shaded coil pole pieces of the motor of Fig. 2 with the disc indicated in dotted lines to illustrate how the motor torque may be adjusted by adjustment of such pole piece; and Fig. 3 65 represents an embodiment of the invention where the end thrust of the worm shaft is opposed by the weight of the worm shaft and the parts carried thereby in a manner to apply a brake to the shaft when the transmitted 70 torque reaches a predetermined desired value.

In Fig. 1 a motor provided with the controlling device of my invention maintains a clock spring wound to a uniform tension. The clock spring unwinds at a rate determined by an escapement to drive the hands of a clock or to operate any other device at a constant rate. The motor represented is an electric motor of the induction disc type comprising a shaded pole stator member 10 75 and a disc rotor member 11 of conducting material such as aluminum. The details of the motor and its control mechanism will be explained more fully in connection with Fig. 2. For the present it will be sufficient to 80 note that the disc is caused to rotate in the direction of the arrow thereon. The rotor 11 is mounted on a shaft 12 which is provided with a worm gear 13 meshing with a gear wheel 14. Gear 14 is connected through reduction gears 15, 16, 17 and 18 to the shaft 19 85 to which the inner end of the clock spring 20 is secured. The outer end of the clock spring is secured to a drum 21 rotatively mounted on shaft 19 and having a gear on its periphery which meshes with a pinion gear 22 mounted on a shaft 23. Shaft 23 is connected through a gear train 24 to an escapement device 25 and through the usual 90 back gear train represented at 26 to the hour 95 100

hand 27. The minute hand 27' is mounted directly on shaft 23.

When the electric motor is energized its armature rotates and winds up the clock spring through the gear train as represented and the clock spring unwinds to operate the escapement and the clock hands or other devices in a well-known manner. No particular form of clock work or escapement is necessary and it will be understood that various changes may be made in these details without departing from the invention. The direction of rotation of the disc 11 and gear 14 represented in Fig. 1 will produce a downward thrust on the worm 13 and its shaft 12 as torque is transmitted from worm 13 to gear 14 and the magnitude of this endwise thrust will of course be proportional to the counter torque of the main spring 20 as transmitted through the gearing to this point. When the main spring is substantially fully wound the counter torque and the end thrust become sufficient to operate the controlling mechanism and slow down the motor to a speed just sufficient to maintain the clock spring wound to this particular tension. This controlling feature will now be explained in connection with Fig. 2.

The induction disc motor stator comprises a U-shaped magnetic frame 28 between the parallel arms of which are supported the core pieces 29 and 30. The alternating current energizing winding 31 is wound on core piece 29 and the two core pieces are separated by an air gap in which the disc 11 rotates. Shading coils indicated at 32 and 33 are provided on one or both pole pieces adjacent the air gap so as to convert the alternating flux therethrough to a shifting flux. Where desirable one or both of these pole pieces may be adjusted for the purpose of varying the motor torque in the manner indicated in Fig. 2. The full line position of the shaded coil pole piece represents the maximum flux shifting position in the direction of rotation of the disc and corresponds to maximum motor torque. The dotted line position of the pole piece represents the nature of the adjustment to reduce the motor torque. Such adjustments can be readily made for example by loosening the nut shown at 42, Fig. 2, and turning the pole piece in the manner indicated in Fig. 2. The shifting flux cuts the rotor disc 11 and returns through the magnetic framework 28. The shifting flux cutting the disc causes its rotation in a well-known manner. The parallel arms of the framework are extended to support the bearings 34 and 35 for the rotor shaft 12. This shaft is preferably made of non-magnetic material. The upper bearing 34 is merely a guide bearing which permits the shaft to move endwise. The bearing 34 is both a guide and thrust bearing the thrust of the shaft being against a ball 36 which is backed

by a spring 37. The tension of the spring is adjustable by means of the screw cap 38 and both the upper and lower bearings are vertically adjustable in the supporting framework. The bearings are adjusted so that when the clock spring is unwound or only partially wound the disc 11 is free to rotate in the air gap without touching the pole pieces. This condition is represented in full lines in Fig. 2.

It will now be apparent that when the disc rotates in a clockwise direction, as observed from the top, the worm 13 will cause gear 14 to rotate in a counterclockwise direction, or so that the peripheral portion which meshes with the worm moves upward. If the disc 11 rotates the gear 14 must either turn as indicated by the arrow thereon, or the worm 13 must move downward as indicated by the arrow 13' adjacent thereto. This arrow may represent the end thrust incident to transmitting torque from shaft 12 to gear 14 and is equal to the counter torque of the clock spring 20 at this point. This end thrust is opposed by the thrust bearing spring 37. When the clock spring 20, Fig. 1, is in an unwound condition the torque condition between 13 and 14 and consequently the end thrust 13' is not sufficient to compress the spring 37 materially, but as the clock spring is wound up and its counter torque increases, the end thrust also increases and the motor shaft, together with the worm and disc, move downward compressing spring 37 until the disc 11 rubs against the lower pole piece 30 and brakes the motor as indicated in dotted lines in Fig. 2. The motor then slows down and rotates just fast enough to maintain the clock spring wound to the tension corresponding to this condition. The spring 37 is preferably adjusted so that this condition usually exists when the clock spring is substantially fully wound. The spring 37 in effect measures the tension of spring 20 and the motor is regulated accordingly.

Where clocks are manufactured in large quantities it may happen that there will be some variation in the strength of the clock springs selected for use at 20 and some variation in the characteristics of the escapement mechanism and in some cases these irregularities may be such that the proper regulation can not be obtained with the usual escapement adjustment indicated at 25'. The adjustment provided at 37 affords another means of regulating the clock mechanism to a limited extent and permits the use of clock springs or escapements which might otherwise have to be discarded. This additional regulation is possible by reason of the fact that by adjusting the spring tension at 37 I may vary the tension at which spring 20 will normally operate and in some cases this may be somewhat less than the tension corresponding to a substantially wound condition.

Instead of allowing the disc 11 to rub directly against the pole piece 30 I prefer to face this surface with a soft friction material which will not scratch the disc or make any noise. I have found that a piece of paper pasted over the pole face as indicated at 39 gives the desired results. It will be understood that the forces involved are very small and that this friction braking action is not sufficient to injure the paper or the disc. If the disc is not exactly true it may alternately start and stop instead of running slowly at a very slow speed when the regulator comes into operation. In either case the regulation is such that the clock spring is maintained at an extremely uniform tension. It will be apparent that this regulation is practically independent of variations in motor torque which might result from variations in voltage, frequency, wave form, or temperature. All excess torque of the motor above that required to maintain the clock spring wound to the desired tension is absorbed by the friction brake. It will also be evident that this regulation is likewise independent of any inherent variation in the resiliency or strength of the clock spring 20 such as might occur due to age or to temperature variations. Thus, if the clock spring should gradually weaken with age it is simply kept wound to a slightly greater amount because the regulation is dependent solely upon the counter torque and not upon any particular rotative relation between the inner and outer ends of the spring 20.

As a result of a constant clock spring tension the escapement is always subjected to exactly the same torque condition and may therefore be of a very simple and inexpensive design and still give excellent time keeping results. In fact, the entire clock work may be of a simple and inexpensive construction involving less gearing and a smaller main spring than is usually employed in hand wound clocks. It is generally desirable however to provide a clock spring at 20 which will operate the clock for a few hours without rewinding.

It will be understood that the electric motor is intended to be normally constantly energized from a suitable source of electricity such as the usual lighting circuit as represented in Fig. 1. In case such source of electricity should fail, as it does occasionally, the motor will naturally stop. However, the clock will continue to operate until the spring 20 is unwound and I prefer to employ a spring that will maintain the clock in operation for about six hours, if necessary, without rewinding. In the event of a failure of the electric supply and the consequent failure of motor torque the clock spring can not unwind by driving the motor backward. The worm gear at 13 constitutes an irreversible

drive and prevents any backward unwinding of the clock spring.

The motor shaft 12 is shown in a vertical position in Fig. 2. This is not essential because the operation of the control mechanism is not intended to be dependent in any way on the weight of the rotating parts. For example, the device of Fig. 2 might be turned up side down. Possibly the spring tension at 37 would then need to be readjusted to a slightly lower value because the regulating end thrust movement would then operate against the weight of the shaft instead of with it. The shaft 12 might also be placed in a horizontal or inclined position.

In Fig. 3 I have represented an embodiment of the invention where the weight of the rotating parts takes the place of the spring thrust bearing of Fig. 2. In Fig. 3 the pitch of the worm 13 is reversed from that shown in Fig. 2 so that for the same direction of rotation the end thrust 13' due to the transmission of torque is up instead of down. When this end thrust is sufficient to raise the rotating parts in the bearings the rotating gear 11' comes against a brake 39' and retards the speed. In Fig. 3 a direct current motor 40 is represented as the driving motor and the drive is through a pinion gear 41 instead of being direct as in Fig. 2. The brake may be applied at any point in the drive train between the motor and the worm.

The arrangement shown in Fig. 2 comprising an induction disc motor with its armature mounted directly on the worm shaft is the preferable arrangement because of its extreme simplicity and compactness. Likewise the spring thrust bearing of Fig. 2 is preferable to the weight of Fig. 3 because of its ease of adjustment and freedom from position requirements. I have found that with the winding motor of Fig. 2 a complete clock movement and winding motor may be built and mounted in the same space ordinarily required for a small hand wound clock movement. The electric motor is preferably mounted between the usual clock plates and serves the beneficial purpose of keeping the clock plate slightly warm which is desirable from the standpoint of lubrication.

In accordance with the provisions of the patent statutes, I have described the principle of operation of my invention, together with the apparatus which I now consider to represent the best embodiment thereof; but I desire to have it understood that the apparatus shown and described is only illustrative and that the invention may be carried out by other means.

Where I have specified a clock movement I intend to include timing movements in general; for example, the movement is suitable for operating time switches or for driving the charts of recording instruments at a constant rate or for establishing the time in

terval for demand meters and for many other purposes.

What I claim as new and desire to secure by Letters Patent of the United States is:

- 5 1. In a spring driven clock movement, a driving spring and means for maintaining said spring wound to a uniform tension comprising an induction motor having a stationary field member with spaced pole pieces separated by an air gap, an armature member mounted for rotation within said air gap, a shaft on which said armature member is mounted, guide bearings for said shaft which permits limited endwise movement thereof, a worm gear mounted on said shaft and meshing with a gear wheel for winding up said spring, the arrangement producing an endwise thrust on said shaft as the spring is being wound, yielding means for opposing endwise movement of said shaft, the parts being adjusted so that the armature member moves against one of the adjacent pole pieces to brake the motor when the end thrust exceeds a predetermined amount.
- 10 2. In a spring driven clock movement, a driving spring, and means for maintaining said spring wound to a uniform tension comprising a normally constantly energized induction disc motor having a stator member with pole pieces separated by an air gap, an induction disc rotatably mounted in said air gap, a shaft on which said disc is mounted, guide bearings for said shaft which permit limited endwise movement thereof, a resilient thrust bearing at one end of said shaft, a worm gear on said shaft meshing with a gear wheel for winding said spring, the direction of rotation of said motor being such that the end thrust incident to the winding up of said 15 spring is against said thrust bearing, the parts being adjusted so that the armature moves against one of the adjacent pole pieces to brake the motor as the end thrust approaches a value corresponding to a predetermined tension of said spring.
- 20 3. In a clock mechanism an induction disc motor comprising a magnetic frame, pole pieces separated by a narrow air gap supported in said frame, an energizing winding for said motor, a shaft having bearings supported in said frame, a disc rotor on said shaft extending into said air gap adjacent the pole pieces, the adjacent rotary and stationary parts of said motor comprising a 25 brake for said motor and means for moving said shaft endwise for applying said brake.
- 30 4. In a clock mechanism, an induction disc motor comprising a stationary part having spaced pole pieces separated by a narrow air gap, an energizing winding for producing a flux across said gap, a disc armature rotatably mounted in said air gap adjacent the faces of said pole pieces, a shaft for said armature adapted to move endwise in response to the 35 torque of said motor, a brake for said motor

comprising the adjacent rotary and stationary parts of said motor, and a non-metallic friction surface covering the stationary part of said motor against which the disc moves when the brake is applied.

5. In a clock mechanism, an induction disc motor comprising a stationary magnetic field member having pole pieces separated by a narrow air gap, an induction disc rotor rotatably mounted in said air gap, and means responsive to the torque of said motor for moving said disc in a direction parallel to its axis of rotation so as to bring its surface against one of the adjacent pole pieces when the motor torque exceeds a predetermined amount.

6. In a clock mechanism, an induction disc motor comprising a U-shaped frame, pole pieces separated by a narrow air gap supported between the parallel arms of said frame, a non-magnetic shaft rotatably supported between the parallel arms of said frame, an induction disc armature on said shaft extending into said air gap, said shaft having a limited endwise movement sufficient to permit the armature to rub against one of the adjacent pole pieces in the air gap to brake said motor, and means responsive to the torque of said motor for controlling the endwise movement of said shaft.

In witness whereof, I have hereunto set my hand this 15th day of November, 1927.

CHESTER I. HALL.
